DESIGN.

H. DALTON.

FRAME FOR COMBINATION LATHE, DRILLING, AND MILLING MACHINES.

APPLICATION FILED FEB. 18, 1921.

58,461.

Patented July 26, 1921.

Inventor
Hubert Dalton,

By his Attorney

C. P. Goepel

UNITED STATES PATENT OFFICE.

HUBERT DALTON, OF NEW YORK, N. Y.

DESIGN FOR A FRAME FOR COMBINATION LATHE, DRILLING, AND MILLING MACHINES.

58,461.

Specification for Design. Patented July 26, 1921.

Application filed February 18, 1921. Serial No. 446,184. Term of patent 14 years.

To all whom it may concern:

Be it known that I, HUBERT DALTON, a citizen of the United States, and a resident of the city, county, and State of New York, have invented a certain new, original, and ornamental Design for a Frame for Combination Lathe, Drilling and Milling Machines, of which the following is a specification, reference being had to the accompanying drawing, forming part thereof.

In the drawing—

Figure 1 is a front elevation thereof, and Fig. 2 is a side or end elevation of a frame for combination lathe, drilling and milling machine, showing my new design.

I claim:

The ornamental design for frames for combination lathe, drilling and milling machines, as shown.

HUBERT DALTON.
